United States Patent Office.

HARLOW FRENCH AND ROBERT MEYER, OF BUFFALO, NEW YORK.

Letters Patent No. 98,048, dated December 21, 1869.

IMPROVED SHIFTING-RAIL FOR BUGGIES.

The Schedule referred to in these Letters Patent and making part of the same.

To whom it may concern:

Be it known that we, HARLOW FRENCH and ROBERT MEYER, of Buffalo, in the county of Erie, in the State of New York, have invented certain new and useful Improvements in Shifting-Rails for Buggies or Carriages; and we do hereby declare that the following description thereof is sufficiently clear and exact to enable others skilled in the art to which it appertains, or to which it is most nearly connected, to make, construct and use the same, reference being had to the accompanying drawings, and to the letters of reference marked thereon, making a part of this specification, in which—

Figure 1 represents a perspective view, and

Figure 2, a plan or top view of our said invention.

The nature of our invention consists in constructing a removable shifting-rail, with the prop-blocks, and slat-irons, or supports for the top of the carriage, in one piece, thereby insuring strength, durability, and simplicity of construction.

In the accompanying drawings, in which like letters in the several figures represent like parts in each—

A represents the seat.

B, the back.

C C and C C the frame-work supporting the back.

D represents the removable rail.

E, the holes through which the ends of the frame-work pass.

They also pass through the stays F, to be fastened

by nuts marked G, which draw the shoulder H down against it, and thereby hold it in place.

The projections J J and K K represent the supports, to which the top of the carriage is fastened.

The number of supports marked C, and the holes through the rail, marked E, may be varied, if desired, without altering the nature of the invention.

It will be readily seen that the shifting-rail can be taken off, together with the top of the buggy, if required, and the back be returned to its place, and fastened by the nuts G, so that the top can at any time be taken and repaired without the necessity of taking the back of the seat off with it, as in the old method of constructing carriage-rails.

Having described our invention with sufficient clearness to enable others skilled in the art to construct and use the same,

What we claim as our invention, and desire to secure by Letters Patent, is—

The removable shifting-rail D, provided with the holes E, and having the projections J J and K K, (or slat-irons and props for the top,) all formed or constructed of one piece, substantially as and for the purposes described.

HARLOW FRENCH.
ROBERT MEYER.
